MOLD SUPPORT AND SEPARATING DEVICE

Louie Wohine, Weston, W. Va.

Application March 26, 1937, Serial No. 133,243

4 Claims. (Cl. 49—42)

The present invention relates to a mold support and separating device which is especially adapted for use in connection with molds employed or used in the manufacture of glassware.

5 One of the objects of the present invention is to provide a device of this character which will enable the operator at predetermined intervals during the blowing operation to open and close the mold sections with facility.

10 A still further important object of the invention is to provide a structure of this character which enables the operator to have free use of his hands for the blowing operation and to control the opening and closing of the mold sections by 15 means of the feet.

A still further important object of the invention will be found to reside in the novel frame supporting structure and the arrangement of the mold and operating levers therefor permitting of the efficient operation of the workman therewith.

20 The present invention contemplates the provision of a suitable platform on which the workman may stand and on which there is arranged in a novel manner the mold especially constructed for the molding of thin glassware in one piece. On the platform are arranged suitable actuating levers for opening and closing the sectional mold sections of the stem mold, and for opening and closing the blow-heads of the body mold, said 25 operating levers being arranged on the platform at a convenient position with respect to the operator for efficient workmanship.

In the accompanying drawings wherein like reference numerals designate similar parts 30 throughout:

Figure 1 is a front elevational view of the device.

Figure 2 is a horizontal sectional view thereof.

Figure 3 is a vertical sectional view taken on 40 the line 3—3 of Figure 1.

Figure 4 is a horizontal sectional view showing the position of the bowl sections in open position, and

Figure 5 is a detail perspective view of the 45 spring leaf operating levers.

In the accompanying drawings wherein for the purpose of illustration there is shown a preferred embodiment of the invention, the reference numeral 6 generally designates the supporting table 50 which includes a top 8 having secured on the underneath side thereof adjacent the rear and front edges transversely disposed angle irons 10. From the underneath side of the top 8 and secured to the angle irons 10 are legs 12. As will be observed these legs 12 are constructed of angle iron

and have secured in spaced relation from the lower ends thereof transversely extending angle iron supports 16. Upon the supports 16 are arranged the angle iron members 18. As will be observed, these members project outwardly from the front portion and have secured transversely thereof to the free end a cross member of angle iron construction 22. At the intersections of the legs and the members 18 there is further secured another angle iron cross member 26 forming a 10 support for the mold platform 28. Upon this mold platform there is secured a mold support and mold structure of the type fully disclosed and described in my pending application. Briefly, this includes as illustrated a pair of spaced pedestals 30 and 32 which are secured to the platform 28 and rise therefrom on the upper end of which by means of bolts 34 there is secured a plate 36 which has a central opening therein. A shell 38 of cylindrical shape rises around concentrically 15 of the opening in the plate in which there is rotatably mounted the body mold. Above the shell 38 the rotatably mounted body mold 37 has on opposite diametrically disposed sides pivotally mounted thereto the sections 40 and 42 forming 20 the head. As clearly illustrated the sections are provided with laterally extending arms 46 for a purpose to be more fully hereinafter described.

The stem mold is formed of semi-cylindrical half-sections 48 and 49 each section having an 25 apertured ear 50 respectively turning on a common pivot 52 which is secured to the support 28.

Extending transversely of the member 18 and secured thereto is a rod 60 having secured centrally thereon spaced collars 64 and 66. These 30 collars as clearly illustrated are secured in position on the rod 60 by means of the set screws 66 and have arranged in the upper portion thereof transversely extending slots in which there are secured upstanding leaf spring members 68 which 35 are secured within the slots by means of the screw bolts 70. The members 68 are provided in their upper free ends with spaced eyes 72 separated by means of a longitudinally extending slot 74. The spring members 64 and 66 are connected to 40 the lugs 54 and 56 of the sectional stem mold sections by means of the links 74. As will be observed the links are downturned at one end and are received in the apertures in the lugs and at the other end are provided with eyes which are 45 received in the slot 74 and secured therein by means of a bolt extending through the eyes 72 and the eyes in the links. To the rod 60 adjacent one end thereof there is secured another collar 80 by means of a set screw 82 and having in 50

the slotted end thereof a horizontally extending spring leaf member of similar construction 84. It will be observed that this spring member 84 extends horizontally and forwardly and has pivotally mounted at the free end thereof the free end of an operating rod 86. This rod extends upwardly through an aperture in the table and is provided on its upper end thereof with a head 88. The sectional mold sections are normally 5 maintained in their open position by means of the spring 90 which has one end secured to an extended portion of one of the levers 74 and the other end, to the rear transversely extending angle iron member 16. It will thus be seen, that 10 in the open position of the mold sections the operating lever or rod 86 is in its upwardly extended position the bowl section being adapted to be closed upon a depressing of the head 88. It is to be noted further that the leaf springs 64, 66 and 15 84 permit of an abrupt and positive closing of the bowl sections and a snap action opening of the same upon the release of foot pressure from the operating head 88.

It will be observed that the head sections 40 and 42 are normally maintained in their closed 20 position by their respective weights. The head sections are adapted to be opened and permitted to close by means of gravity through the operating mechanism which includes a semi-circular shaped cross head 96 having secured thereto by 25 means of screw bolts depending pins 98 which pins are adapted to engage the laterally extending arms 46 of the head sections. Adjacent the free ends of the cross member 96 there are secured 30 upwardly extending arms 100 and 102. These arms extend upwardly through apertures in the platform or top 8 and on the arm 102 there is secured a head 104. Between the head 104 and the top of the table 8 there is provided a spring 35 106 encircling the arm 102 normally maintaining the member 96 in an uppermost position and holding the pins 98 out of engagement with the arms 46 of the head sections permitting the head sections to assume their normally closed position 40 by means of gravity. Upon a depressing of the head 104 the pins 98 contact the arms 46 opening the head sections. In the central portion of the front end of the table 8 there is provided an inwardly directed V-shaped slot 110. 45 This slot as will be observed, is directly above the U-shaped cross head member and permits of access from the front end and top of the table to the head of the mold.

In operation, the head sections are normally 50 maintained in their closed position by gravity, the operator standing on top of the table 8 closing the sections of the sectional stem mold by depressing the head 88. The operator after obtaining a sufficient quantity of molten glass on 55 the free end of his blow pipe inserts the same through the mold head into the mold and after completing the molding operation raises one foot from the head 88 effecting an automatic opening of the mold sections forming the stem 60 of the ware, and upon a depressing of the head 104 by the other foot opens the mold head permitting, of the completed blown ware to be removed from the mold. It will be observed, that 65 the workman or operator's hands are entirely free for the blowing operation, the control of the mold during the molding operation being 70 effected by the feet of the operator.

While there is shown for the purpose of illus-

tration a preferred embodiment of the invention, it will be understood that it is capable of various changes and modifications without departing from the spirit and scope thereof, and it is intended therefore, that only such limitations shall be imposed thereon as are indicated in the prior art or in the appended claims.

What is claimed is:

1. A mold operating device for molds for making stemmed glassware including a shell having 10 a body mold disposed therein, a mold head including a pair of sections pivotally mounted adjacent the upper end of the mold having laterally extending arms, said heads normally closing by gravity, a pair of sectional molds communicating 15 with the body mold and disposed below said body mold, comprising a table, said mold being secured below the top and to one side of said table, a cross head having upwardly extending rods extending through apertures in the top of the table, a head on one of said rods, a coiled spring 20 encircling said rod and disposed between the underneath side of said head and the top of said table for normally urging the cross head in an uppermost position, and depending pins on said cross member cooperating with the pivotally mounted head sections for opening the same upon a depressing of the cross member.

2. A mold operating device for molds having pivotally mounted mold sections comprising a 25 table including legs and a top, said mold being secured to said table adjacent one side thereof and below the top, a rod pivotally mounted to said table, spaced stiff resilient arms secured to said rod, links connecting the free ends of said 30 arms with said mold sections, a stiff resilient actuating arm secured to and extending laterally of said rod, an actuating rod extending through the top of the table and having its free lower end pivotally connected to the laterally extending 35 actuating arm for effecting rotation of the rod, and the closing of said mold sections, and a spring 40 normally urging said sections into open position.

3. A mold operating device for molds having a head including pivotally mounted sections normally closed by gravity, comprising a table including legs and a top, said mold being secured to said table adjacent one side thereof and below the top, a cross member disposed above the pivotally mounted head sections slidably arranged in said table, pins projecting from said cross 50 member for engagement with the sections to open the same, resilient means normally urging said cross member to an inoperative position, and means extending through the top of the table 55 for moving said cross member to an operative position to open said head sections.

4. A mold operating device for molds having pivotally mounted mold sections comprising a support, said mold being secured to said support adjacent one side thereof and below the top, a 60 rod pivotally mounted on said support, spaced stiff resilient arms secured to said rod, links connecting the free ends of said arms with said mold sections, an actuating arm secured to and extending laterally of said rod, an actuating rod extending through the support and having its free lower end pivotally connected to the laterally extending actuating arm for effecting rotation of the pivotally mounted rod, and the closing of said mold sections, and resilient means 65 normally urging said sections in open position.

LOUIE WOHINC.
